(57) **CLAIM**

The ornamental design for a hydrant drain bag, as shown and described.

DESCRIPTION

FIG. 1 is a perspective view of a hydrant drain bag;
FIG. 2 is a front elevational view thereof;
FIG. 3 is a right side elevational view thereof;
FIG. 4 is a rear elevational view thereof;
FIG. 5 is a left side elevational view thereof;
FIG. 6 is a top plan view thereof;
FIG. 7 is a bottom plan view thereof;
FIG. 8 is a left side elevational view thereof;
FIG. 9 is a front elevational view thereof, showing the plane upon which a cross-sectional view is taken and shown in FIG. 10 and FIG. 11;
FIG. 10 is a top cross-sectional view thereof taken along 10-10 of FIG. 9;
FIG. 11 is a perspective cross-sectional view thereof taken along line 11-11 of FIG. 9;
FIG. 12 is a front cross-sectional view thereof taken along line 12-12 of FIG. 8; and,
FIG. 13 is a magnified view of the portion shown and designated in FIG. 12.
